UNITED STATES PATENT OFFICE.

OTTO LUDVIG ZEUTHEN, OF COPENHAGEN, DENMARK.

ROTARY MANIFOLDING MACHINE.

Application filed September 9, 1927, Serial No. 218,535, and in Denmark November 5, 1926.

My invention relates to duplicators or similar manifolding machines of the kind consisting of a rotary drum or cylinder for supporting a stencil, means for pressing the sheet to be printed against the cylinder, for instance a press roller or the like, and means for guiding the fed in sheet, for stopping it in the initial position and for receiving the printed sheet.

The invention has for its object to thus arrange the machine, so as to facilitate printing and the control of the work.

A further object of the invention is to eliminate gears and to prevent soiling of the work.

According to the invention the sheets are turned over so as to be delivered above the fed in sheets to enable the operator to control both the feeding and the delivery from one position.

The turning of the sheets may be obtained by thus arranging the sheet feeding and delivery sides with relation to the press roller or the like so as to form a loop or a U-shaped path. The curving of the sheets may be obtained by special guides, or by their own weight.

The delivery side and the feeding side are arranged with relation to each other and to the drum, or the press roller, that the movement of the sheets during the printing corresponds to a right turning of the drum, which as a matter of course may be obtained by direct hand turning, or without the intermediary of any direction changing gears.

In order to have my invention fully understood I have diagrammatically represented a preferred form thereof in the annexed drawings.

Fig. 1 shows a plan view of the machine.

Figs. 2 and 3 show end views of the machine during inking and printing respectively.

The circumference of the rotary cylinder or drum mounted in stands 4 and directly connected with a handle 5, consists partly of a cylindrical segment 6 for applying the stencil, and partly of a plane or otherwise retracted surface 7, upon which a stop or stops 8 for the fed in sheet are placed near the edge 9. If preferred the stop or stops 8 may be adjustable.

The press roller 10 is mounted in a frame 11 enabling it to be released by means of a suitable cam lever 12, Figs. 2 and 3. According to Fig. 3 the line of contact between the press roller 10 and the segment 6, that is, the line of printing, is positioned on the left side of the matrix or drum somewhat lower than the hori-

zontal middle plane of the latter. The edge 9 is situated immediately below this touching line when the matrix or drum assumes its initial position for each printing operation, or for instance when the handle 5 passes a resilient stop 14, which prevents turning in the opposite direction, or to the left.

To the left of and below the press roller 10 there is positioned a sheet support or feeder 15 curved towards the press roller. At the same side, but somewhat above the press roller there is positioned another sheet support or delivery table 17 provided with a suitable sheet guide or guides 16. If preferred the supports 15 and 17 may be adjustably and removably mounted, which can be attained by known means not necessitating further explanations. In Fig. 2 the support 17 is removed.

In case of a stencil drum the segment 6 may be perforated or consist of wire gauze or the like, and the end walls of the drum may have openings 18 enabling an inking roller 19 to be placed in bearings 20 on the stands 4 so as to be in contact with the wire gauze or the like. When turning the segment 6 alternately in the one and the other direction as indicated by a double arrow 21 of Fig. 2 the ink, introduced into the drum from a tube or the like, will, by the action of the inking roller 19, be regularly distributed all over the segment and thus wet the stencil covering the outer surface of the segment. The inking roller 19, the pins of which may be axially resilient in any known manner, may then be removed from the bearings 20 and placed in bearings 22 in the end walls of the drum as shown in Figs. 1 and 3.

The described machine operates in the following manner.

The operator turns the matrix or drum to the right (arrow 24 of Fig. 3) with his right hand, and with his left hand he introduces successive sheets over the support 15 until they abut the stop 8.

The front edge of every sheet is turned to the left by the edge 9 of the rotating drum, the segment 6 of which, thereafter in connection with the press roller 10, prints the sheets carrying it in the direction shown by dotted lines in Fig. 3, so as to fall on the support 17 with its printed side upwards. The finger or fingers 16 may if necessary limit the course of the printed sheets.

A preferred form of the invention has been illustrated but it is obvious that it may be

altered in various ways without departing from the scope of the invention. The press roller 10 or like means may if desired be arranged above the median plane of the machine instead of below it. Further the delivery side may be arranged under instead of over the feeding side. Further the feeding and the delivery may take place at the right side of the machine in lieu of the left side. Further in lieu of a single drum there may be employed two drums carrying an endless belt upon which the stencil or the like is mounted.

As these and similar alterations will be easily understood without further explanations, they are not shown on the drawing.

What I claim is:

1. A rotary manifolding machine of the kind described, comprising a rotatable cylinder having a stencil supported thereon, a roller cooperating with said cylinder for pressing a sheet to be printed against the cylinder, a feed table, a delivery table disposed above and in alignment with said feed table, said roller being positioned intermediate said tables, means on said feed table for guiding the sheet between the roller and cylinder, and means on said delivery table adjacent said roller for guiding the sheet to the delivery table.

2. A rotary manifolding machine of the kind described, comprising a rotatable cylinder having a stencil supported thereon, a roll-

er cooperating with said cylinder for pressing a sheet to be printed against the cylinder, said cylinder having a transverse recess on its periphery, a stop member in said recess for positioning the sheet with respect to said cylinder, a feed table, a delivery table in vertical alignment with said feed table, said roller being positioned intermediate said tables, means on said feed table for guiding the sheet between the roller and cylinder, and means on said delivery table adjacent said roller for guiding the sheet to the delivery table.

3. A rotary manifolding machine of the kind described, comprising a rotatable cylinder having a stencil supported thereon, a roller cooperating with said cylinder for pressing a sheet to be printed against the cylinder, said cylinder having a flat transverse portion on its periphery, a projecting member secured to said flat portion for positioning the sheet with respect to said cylinder, a feed table, a delivery table in vertical alignment with said feed table, said roller being positioned intermediate said tables, means on said feed table for guiding the sheet between the roller and cylinder, and means on said delivery table adjacent said roller for guiding the sheet to the delivery table.

In testimony whereof I hereunto affix my signature.

OTTO LUDVIG ZEUTHEN.
